US0D1001121S

(12) **United States Design Patent** (10) **Patent No.:** **US D1,001,121 S**
(45) **Date of Patent:** **** Oct. 10, 2023**

(54) **DATA PROCESSING DEVICE**

(71) Applicant: **SITA IT SERVICES CANADA INC.**,
Quebec (CA)

(72) Inventors: **Kirk Mosna**, Hamilton (CA); **Steve Orzel**, Hamilton (CA); **Graham Hills**,
Hamilton (CA); **Alejandro Jose Caceres**, Montreal (CA); **Harmandeep Dhaliwal**, Montreal (CA); **Daniel Albines**, Montreal (CA); **Matthew Joseph Salari**, Montreal (CA); **Ezana Tekie Tesfay**, Montreal (CA)

(73) Assignee: **SITA IT Services Canada Inc.** (CA)

(**) Term: **15 Years**

(21) Appl. No.: **29/695,215**

(22) Filed: **Jun. 17, 2019**

(30) **Foreign Application Priority Data**

Dec. 17, 2018 (EM) 005910783-0001

(51) **LOC (14) Cl.** **14-02**

(52) **U.S. Cl.** **D14/302**
USPC ..

(57) **CLAIM**

The ornamental design for a data processing device as shown and described.

DESCRIPTION

FIG. 1 is a perspective view of an embodiment of a data processing device.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

The broken lines, including the ventilation hole patterns shown in FIGS. 1-8, represent portions of the data processing device and form no part of the claimed design.

1 Claim, 8 Drawing Sheets
